UNITED STATES PATENT OFFICE.

STEPHEN A. FOSTER, OF TOLEDO, OHIO.

DESIGN FOR A TAG.

SPECIFICATION forming part of Design No. 25,819, dated July 21, 1896.

Application filed April 6, 1896. Serial No. 586,465. Term of patent 14 years.

To all whom it may concern:

Be it known that I, STEPHEN A. FOSTER, of Toledo, county of Lucas, and State of Ohio, have invented a certain new and original 5 Design for Seal-Tags; and I do hereby declare that the following is a full, clear, and exact description of the invention, which will enable others skilled in the art to which it appertains to make and use the same, reference 10 being had to the accompanying drawings, and to the figures of reference marked thereon, which form part of this specification.

This design relates to a seal-tag, and, as shown in the drawings, Figure 1 is a perspective view of the tag, showing my design. Fig. 15 2 is a sectional elevation in further illustration of the same.

The leading feature of my design consists in a sheet of metal in substantially U form 20 in side elevation, each side portion of the body provided from the bend with substantially parallel sides, the ends of the metal sheet being enlarged in the form of a circle. One side is provided with a depending annular 25 projection, the perforation therein extending through the body of the side, and the opposite side provided with a circular orifice, whereby the tag, when viewed from either lower or upper side, presents an unbroken 30 continuous surface.

1 designates the body of the tag of U form, when viewed in side elevation, one-half of the tag comprising a body having parallel sides and a circular end portion from which depends an annular projection 2, the orifice 35 therin extending through the side of the body from which it depends.

The metal of the upper surface of the side of the tag surrounding the orifice within the depending projection is curved outwardly 40 from the orifice, as shown at 3, whereby the visible portion of the upper face of the tag presents a smooth continuous surface. The lower section of the tag is provided with an orifice in circular alignment and of equal diameter with the exterior of the depending annular projection 2 upon the opposite side. 45

What I claim is—

The design for a tag substantially as shown and described.

In testimony that I claim the foregoing as my own I hereby affix my signature in presence of two witnesses.

STEPHEN A. FOSTER.
